UNITED STATES PATENT OFFICE.

ARGYLE CAMPBELL, OF CHICAGO, ILLINOIS, ASSIGNOR TO ENTERPRISE RAILWAY EQUIPMENT COMPANY, OF CHICAGO, ILLINOIS.

CAR.

1,342,089.

Specification of Letters Patent.

Patented June 1, 1920.

Application filed May 19, 1919. Serial No. 298,181.

To all whom it may concern:

Be it known that I, ARGYLE CAMPBELL, a citizen of the United States, residing at Chicago, in the county of Cook and State 5 of Illinois, have invented a certain new and useful Improvement in Cars, of which the following is a full, clear, concise, and exact description, reference being had to the accompanying drawings, forming a part of 10 this specification.

This invention relates to improvements in cars.

One object of the invention is to provide a freight car of the box type especially 15 adapted for the carrying of grain or other bulk material adapted to be discharged through a hopper.

Another object of the invention is to provide a car having hopper door mechanism 20 of a novel and highly efficient and easily-operable type.

Still another object of the invention is to provide a hopper car adapted for the carrying 25 of grain and like materials wherein an efficient grain seal is formed around the door closure.

The invention furthermore consists in the improvements in the parts and devices 30 and in the novel combinations of the parts and devices herein shown, described and made the subject matter of claim.

In the drawings forming a part of this specification, Figure 1 is a side elevation of approximately one-half of a car embodying 35 my improvements. Fig. 2 is an end elevational view of the improved car. Fig. 3 is a vertical transverse sectional view taken through the body bolster and illustrating one-half of the car, the section being upon 40 a larger scale than the end elevation shown in Fig. 2. Fig. 4 is an enlarged detail sectional view taken through one of the hoppers and more clearly illustrates the hopper doors and operating mechanism therefor, 45 the section corresponding substantially to the section taken on line 4-4 of Fig. 1. Fig. 5 is a longitudinal vertical detail sectional view upon an enlarged scale and taken approximately on line 5-5 of Fig. 4. And 50 Fig. 6 is a plan floor view of a section of approximately one-half of the car to illustrate the arrangement of hoppers.

In said drawings, the car body is shown as made entirely of metal and has sheet 55 metal side walls 10-10, sheet metal end

walls 11-11, a sheet metal roof 12, channel center sills 13-13 having a cover plate 14 and ridge-shaped diverting boards 15 extending lengthwise of the center sills. The underframe of the car also involves bolsters 60 16 and cross bearers or needle beams 17-17, the latter being located between transverse sets of hoppers, as clearly illustrated in Figs. 1 and 5. It will be noted that the car which I have chosen to illustrate my invention differs from the usual box car in that it has no side or end doors, but, in fact, is closed on all sides thereof. In carrying out my invention, the grain or other bulk material will preferably be introduced at the 70 top of the car—as, for instance, through the opening or hatch indicated diagrammatically at 18 in the roof of the car in Fig. 1. As indicated by Figs. 1 and 6, the car is preferably provided with eight hoppers, 75 four on each side of the center sill extending lengthwise of the car. Each of these hoppers differs from the ordinary construction of hoppers in that there is a true hopper section proper and below the hopper 80 section proper what may be termed a discharge mouth. Each of said hoppers is formed by oppositely and downwardly inclined end hopper sheets 19-19, an outer inwardly and downwardly inclined hopper 85 sheet 20 and an inner downwardly and outwardly inclined hopper sheet 21. The end hopper sheets of the hoppers nearest the end of the car form a continuation of what may be termed the inclined 90 floor 22 of the car, as shown in Fig. 1, said floor being extended to the end wall 11 and united therewith, as will be understood. The other end hopper sheets 19 of the hoppers are extended up to, and united with, 95 vertical partitions 23 in the car which extend from the side thereof. These partitions extend upwardly a greater part of the height of the car, but not to the roof thereof, as shown in Fig. 1. The outer hopper 100 sheets 20 extend up to the side walls 10 of the car and are united thereto, and the inner hopper sheets 21 are extended up to the center sills and united to the latter. As will be evident from the foregoing, the 105 hopper sheets 19, 20 and 21 form a four-sided hopper with all of the sides converging.

The discharge mouth of each hopper is formed by continuing the outer hopper 110

- sheet 20 downwardly, as indicated at 24, until the lower edge thereof is approximately in the plane, extended, of the inner hopper sheet 21. The sides of the discharge mouth are formed by vertically extending substantially triangular sheets 25-25, secured, at their upper edges, to the lower edges of the end hopper sheets 19. As will be evident from an inspection of Fig. 4, the inner hopper sheet 21 terminates at a sufficient distance above the lower edge of the outer hopper sheet to provide an opening through which the grain or other bulk material may be discharged.
- 15 As is well known, it is necessary to provide a seal to prevent leakage of grain and other similar bulk material while the car is in transit. To accomplish this result, I have provided a novel arrangement as follows:
- 20 surrounding the door opening above mentioned, is a casting 26 having a suitable flange adapted to be riveted to the outer sides of the hopper sheet 20, end hopper sheets 19, vertical sheets 25 and the under-
- 25 side of the inner hopper sheet 21—said flange being indicated at 27. Said casting is extended beyond the opening proper and is provided on three sides of the opening with an outwardly flaring flange 28, the inner surfaces thereof, on said three sides, being flat, as evinced from an inspection of Fig. 4. Along the upper horizontal edge of the door opening, said casting 26 is provided with a convex flange 29 and also with suitable
- 30 hinge lugs 30-30. The coöperating door indicated by the reference 31 is also preferably in the form of a casting and on three sides thereof is provided with beveled or inclined flanges 32 coöperable with the flaring flanges 28 of the casting 26. Along its upper horizontal edge the door 31 is provided with a concave flange 33 coöperable with the convex flange 29 of the casting 26. The convex flange 29 and concave flange 33
- 35 are struck on radii, the center of which coincides with the pivotal axis 34 of the hinges for the door, it being understood that the door 31 has suitable hinge lugs 35 adapted to be connected to the corresponding hinge lugs 30 by a pin or other suitable connection. From the foregoing description, it will be evident that as the door is moved to closed position, it will be wedged on three sides by the inclined flanges and a seal will
- 40 always be maintained in any position of the door along the upper edge by means of the curved flanges 29 and 33. This arrangement provides a cheap construction, easily manufactured and applied.
- 45 60 For operating the doors, I preferably provide two duplicate sets of mechanisms so that four doors are operated at a time. Inasmuch as these mechanisms are both alike, it will only be necessary to describe one of them in detail. Referring particularly to

Figs. 4 and 5, it will be seen that the mechanism for each set of hopper doors comprises the following arrangement: secured to the lower flanges of the center sill 13 are cross plates 36, to which in turn are secured longitudinally spaced sets of depending plates 37-37, united at their lower ends by a U-shaped plate 38. The depending vertical plates 37 are slotted, as indicated at 39, within which slots are adapted to slide, up and down, pins 40. Each pin 40 is carried by a pair of short links 41 which are pivoted, as indicated at 42, to a lever arm 43 rigid with a longitudinally extending shaft 44. The shaft 44 is mounted in suitable bearing brackets 45 that are attached to suitable cross plates on the under sides of the center sills and to the inner hopper sheets 21. Additional bearing brackets 46 may be provided for the shaft intermediate 80 those referenced 45. Pivoted connected to the pins 40 are oppositely extending struts 47, one to each door, said struts 41 being each preferably threaded at its outer end, as indicated at 48, and thereby adjustable 85 within a sleeve 49, that is in turn pivotally connected, as indicated at 150, to the corresponding door 31.

For rotating each shaft 44, I provide a transversely extending operating shaft 50. Said shaft 50 is mounted in a suitable bearing 51 at its outer end, as indicated in Fig. 4, and is extended through the nearest center sill 13 and has its inner end seated in a bearing 52 carried by the inner face of the remote center sill 13. Said operating shaft 50 may be provided with any suitable form of pawl or ratchet mechanism and locking device at its outer end, the same being indicated at 53 in Fig. 4. Mounted on the shaft 50 are two sheave wheels 54 and 55, one being on the outer side of the center sill and the other on the inner side thereof, as clearly illustrated in Fig. 4. From the sheave wheels 54 and 55 run chains 56 to a corresponding pair of sheave wheels 57 and 58 carried by the longitudinal shaft 44, the sheave wheels 57 and 58 being, of course, in planes at right angles to the planes of the sheave wheels 54 and 55. They are arranged, however, so that lines can be drawn tangential to the surfaces of the corresponding sets of sheave wheels, as will be clear from an inspection of Figs. 4 and 5. One of said chains 56 is used when the shaft 44 is to be rotated in one direction and the other chain comes into play when said shaft 44 is rotated in the opposite direction. As will be obvious, rotation of the shaft 44, as viewed in Fig. 4, in a counter-clockwise direction 110 will elevate the lever arm 43 and break or collapse the strut between the opposed sets of doors 31 and permit the latter to open.

Although I have herein shown and described what I now consider the preferred 130

manner of carrying out the invention, the same is merely illustrative and I contemplate all changes and modifications that come within the scope of the claims appended hereto.

5 I claim:

1. In a car of the character described, having hoppers on opposite sides of the center sills provided with center dumping hopper doors disposed in transverse alignment, the combination with a transversely extending operating shaft disposed between pairs of hoppers, said shaft being mounted at its inner end in bearings carried by the center sills 10 and extending through one of the center sills, of sheave wheels carried by said shaft, one being located outside of a center sill and the other on the inner side thereof, a longitudinally extending operating shaft disposed below the transverse shaft and having a pair of sheave wheels thereon, flexible connections extending between said sheave wheels, said longitudinally extending shaft being disposed beneath the center sill 15 through which the transverse shaft is extended, and link connections from said longitudinally extending shaft to the sets of hopper doors for operating the latter simultaneously.
2. A car of the character described having a plurality of hoppers on opposite sides of the center sills and arranged in pairs transversely of the car, each of said hoppers having a discharge opening facing toward the center of the car and located below the center sills thereof, the combination with doors for each of said openings, the doors being pivotally mounted along their upper edges to swing about axes parallel with the center sills and below the latter, of mechanism for 20 operating said doors, said mechanism in-

cluding, a transversely extending operating shaft journaled at its inner end on the center sills and extending through one of them, sheave wheels mounted on said shaft, one between the center sills and the other outside thereof, a longitudinally extending shaft mounted beneath the center sill through which the transverse shaft extends, sheave wheels on said longitudinally extending shaft, flexible connections between said sheave wheels, and means interposed between said longitudinally extending shaft and the doors, said means being located below the center sills.

3. A car of the character described having a plurality of hoppers in the bottom thereof, each hopper being formed by two end oppositely and downwardly inclined hopper sheets, an outer hopper sheet extending 30 downwardly and inwardly from the side wall of the car, and an inner hopper sheet extending outwardly and downwardly from the center sill, whereby all four sides of each hopper converge to a point below the center sills 35 and car side; each hopper having also a discharge mouth at the bottom thereof composed of a continuation of said outer hopper sheet and two additional substantially triangular sheets extending transversely of 40 the car and secured to the respective lower edges of said end hopper sheets, each discharge mouth having a rectangular discharge opening facing toward the center of the car; a pivotally mounted door for each 45 of said openings; and mechanism for operating the doors.

In witness that I claim the foregoing I have hereunto subscribed my name this 12th day of May, 1919.

ARGYLE CAMPBELL.
